United States Patent Office

Des. 216,293
Patented Dec. 16, 1969

216,293

GATE LATCH

Bennie L. Blackston, R.R. 3, Augusta, Kans. 66104

Filed Feb. 4, 1969, Ser. No. 15,617

Term of patent 14 years

Int. Cl. D8—03

U.S. Cl. D8—131

FIGURE 1 is a perspective view of a gate latch;
FIGURE 2 is a side elevational view thereof; and
FIGURE 3 is a rear elevational view.

The broken line showing of a fence is for illustrative purposes only.

I claim:

The ornamental design for a gate latch, as shown and described.
